HEDDLE BAR SUPPORT

Ralph Ragan, Atlanta, Ga., assignor to Steel
Heddle Manufacturing Company, Philadelphia,
Pa., a corporation of Pennsylvania

Application December 6, 1932, Serial No. 645,906

10 Claims. (Cl. 139—92)

This invention relates to means for supporting the heddle bars in the heddle frames of looms.

One of the principal objects of my invention is to provide a heddle frame having an extremely simple and inexpensive, and at the same time efficient, supporting and locking means for connecting the heddle bars to, and holding them rigid with, the top and bottom rails of the heddle frame.

A further object of the invention is to provide a heddle bar supporting and locking means which occupies minimum space, has no projecting parts which might foul an adjacent frame of the loom, should the support turn partially sideways, and which can therefore be used with very narrow frames, and one which will adequately lock and maintain the heddle bar in position, and which, at the same time, may be readily actuated to release the bar.

With these and other objects in view, which will become apparent as the description proceeds, I have illustrated one of the forms that the invention may take, in the accompany drawing, in which,—

Figure 1 represents a fragmentary view in elevation, partly in section, of a portion of a heddle frame, showing my invention applied thereto, one of the heddle bars being shown in position, with some of the heddles disposed thereon.

Figure 2 represents a sectional view on the line 2—2 of Figure 1, looking in the direction indicated by the arrows, the heddles being omitted for clearness of illustration.

Figure 3 represents a similar view on the line 3—3 of Figure 1.

Figure 4 represents a horizontal sectional view taken on the line 4—4 of Figure 3.

Referring more particularly to the drawing, one of the rails of a heddle frame, which may be the top rail, is indicated at 5, one of the heddle bars is indicated at 6, and the end portions of some of the heddles are indicated at 7.

The heddle bar support indicated generally at 8, is flattened at its outer end as at 9, and is provided with a recess as at 10 for receiving the heddle bar 6. The lower end of the recess 10 terminates in a beveled shoulder 11 which tends to constantly urge or cam the bar against the support when the former is locked in place on the support.

The upper end of the recess is cut in a double step as at 12—12', to allow of the bar being readily inserted into and removed from the recess and also to provide a clearance which will allow the lower corner of the locking sleeve as at 16 (after having been bent inwardly slightly toward the

opposite face of the sleeve, as indicated in Fig. 4) to move upwardly when the sleeve is moved into its unlocked position, to sufficiently clear the heddle bar and allow easy removal of the same.

Slidably mounted upon the flattened portion 5 of the support is a locking member 13 which may be in the form of a flattened split sleeve. It may be manufactured from a piece of sheet metal recessed at one end as at 14, and at the other as at 15, and may be formed bent so as to constitute a slidably member for locking the heddle bar in position. The recess 14 is made of such dimensions as to allow clearance for the bulge 15' which occurs at the junction of the flattened portion 9 of the support with the cylindrical portion 10 thereof, and on the opposite side of the locking sleeve 13, the distance between the split edges of the sleeve is sufficient to allow a clearance for the bulge, as shown in Figure 2. The sleeve may thus be moved upwardly sufficiently to clear the 20 heddle bar to allow the latter to be disengaged from the support when it is desired so to do. The lower recess 15 is proportioned to engage over the edge of the heddle bar opposite the edge thereof engaged by the shoulder 11, so as to lock the bar 25 against the support when the sleeve is in the position indicated in the drawing.

On the opposite side of the sleeve from that in which the recess 15 occurs, one edge of the split in the sleeve is so disposed that a corner of the 30 sleeve will engage the heddle bar on the face thereof opposite the one which is against the support, as at 16 (Fig. 3), so that the bar is thus engaged on both sides of the flattened portion of the support or pin and held tightly against the 35 latter.

The support is suitably connected to the rail 5 of the heddle frame, as for instance, by being threaded, as at 17, so as to screw into the frame.

A spring 18 may be utilized to normally constantly urge the locking sleeve against the heddle bar, and this spring at one end bears against a washer 19, which surrounds the cylindrical portion of the support, and which bears upon the upper edge of the sleeve, and at its opposite end the spring engages the protuberances 20 which are formed by clinching the shank of the support, after the washer and spring are assembled thereon, to thus form a bearing or anchorage for the 40 spring and prevent it from slipping along the support under the tension which is developed when the heddle bar is in position.

From the foregoing, it will be understood that by shifting the sleeve upwardly or towards the 55

inner end of the support, the heddle bar will be released and may be removed from the support for sliding the heddles 7 into position on the bar, or for adjusting their position thereon, and that when the bar has been replaced in the recess, by releasing the locking sleeve, it will be forced downwardly by the spring and maintained under the tension thereof in locking engagement with the bar. The pressure against the bar will, due to the action of the beveled shoulder 11, cam or force the bar inwardly against the support and maintain it in locked engagement therewith throughout its width. Thus the bar will be kept in a locked condition in which no loose motion or relative movement between the bar and support is allowed to take place.

In order to prevent the locking sleeve from coming off of the support when the heddle bar is removed, it may, after the support and the various elements of the locking device have been assembled, have its lower corner as at 16, bent inwardly slightly toward the opposite face of the sleeve, as indicated in Figure 4, so as to bring this corner into alignment with the shoulder 11, so that the latter will form a stop to prevent removal of the sleeve from the support.

The foregoing detailed description has been given for purposes of clearness of understanding of the invention, and of the particular embodiment thereof chosen for illustrative purposes, but no undue limitation should be deduced therefrom, as the claims should be construed as broadly as permissible in view of the prior art.

Having thus described my invention what I claim as new and desire to secure by U. S. Letters Patent is:—

1. In a loom heddle frame, a heddle bar upon which the heddles are mounted, and a support for the heddle bar having a flattened portion provided with a recess for receiving the heddle bar, a sleeve slidably mounted on the flattened portion of the support and adapted to engage the heddle bar for locking it in the support, a washer surrounding the support beyond the sleeve and bearing against the latter, a spring surrounding the support beyond the washer and bearing at one end upon the washer, protuberances formed on the support against which the spring bears at its other end, and means other than the heddle bar for limiting movement of the sleeve in the direction in which it is moved by the spring.

2. In a loom heddle frame, a heddle bar upon which the heddles are mounted, and a support for the heddle bar, comprising a pin mounted on a rail of the frame and having a flattened portion provided with a shoulder adapted to engage the heddle bar when the latter is in position on the support, a sleeve slidably mounted on the flattened portion of the pin and adapted to engage the heddle bar for locking it in position on the support, a spring anchored on the pin beyond the flattened portion adapted to normally urge the sleeve into engagement with the heddle bar, and means other than the heddle bar for limiting movement of the sleeve in a direction toward the free end of the pin.

3. In a loom heddle frame, a heddle bar upon which the heddles are mounted, and a support for the heddle bar, comprising a pin mounted on a rail of the frame and having a shoulder adapted to engage the heddle bar when the latter is in position on the support, a sleeve slidably mounted on the pin for movement longitudinally thereof and adapted to engage the heddle bar for holding it in position on the support, a spring

mounted on the pin and adapted to normally urge the sleeve into locking engagement with the heddle bar, and means other than the heddle bar for limiting movement of the sleeve in a direction toward the free end of the pin.

4. In a loom heddle frame, a heddle bar upon which the heddles are mounted, and a support for the heddle bar, comprising a pin having one end flattened and provided with a shoulder adapted to engage the heddle bar when the latter is in position on the support, the other end of the pin adapted to be mounted on a rail of the frame, a sleeve slidably mounted on the flattened portion of the pin and adapted to engage the heddle bar for locking it in position on the support, a spring anchored on the pin beyond the flattened portion adapted to normally urge the sleeve into engagement with the heddle bar, said sleeve being split and being adapted to engage the heddle bar on opposite sides of the flattened portion of the pin, and means other than the heddle bar for limiting movement of the sleeve in a direction toward the free end of the pin.

5. In a loom heddle frame, a heddle bar upon which the heddles are mounted, and a support for the heddle bar having a shoulder for engagement by the heddle bar, a spring-pressed sleeve adapted to engage the bar for locking it in position on the support, a portion of the sleeve being aligned with said shoulder, whereby to prevent accidental removal of the sleeve when the heddle bar is removed from the support.

6. A latch for heddle frames, comprising a shank having a part provided with a recess, adapted to receive a heddle bar, a member slideable with respect to said part and provided with an extension operative to cooperate with that side of a heddle bar directed away from said part when in said recess, and a deflected portion on said latch, operative to limit the movement of said member in a direction toward the free end of said shank.

7. In a loom heddle frame, a heddle bar upon which the heddles are mounted, and a support for the heddle bar having a shoulder for engagement by the heddle bar, a spring-pressed sleeve adapted to engage the bar for locking it in position on the support, and means on the sleeve for preventing accidental removal of the sleeve when the heddle bar is removed from the support.

8. In a loom heddle frame, a heddle bar upon which the heddles are mounted, and a supporting member for the heddle bar having a shoulder for engagement by the heddle bar, a sleeve member mounted on said supporting member and adapted to engage the bar for locking it in position on the supporting member, and means on one of said members for preventing accidental removal of the sleeve when the heddle bar is removed from the support.

9. A latch for heddle frames, comprising a shank member having a shoulder for engagement by a heddle bar, a member slideable with respect to said shank and provided with an extension operative to cooperate with that side of the heddle bar directed away from said shoulder and means on one of said members operative to limit the movement of said slideable member in a direction toward the free end of said shank.

10. In a loom heddle frame, a heddle bar upon which the heddles are mounted, a support for the heddle bar comprising a pin having one end flattened and provided with a shoulder adapted to engage the heddle bar when the latter is in

position on the support, the other end of the pin being mounted on a rail of the frame, a sleeve 5
slidably mounted on the flattened portion of the pin and having a portion engaging the heddle
bar for locking it in position against said shoulder, a washer mounted on said pin at one end
of said sleeve and a spring mounted on said pin, one end of said spring being anchored on said
pin beyond the flattened portion and the other
10 end of said spring bearing on said washer to

urge said sleeve into engagement with the heddle
bar, said sleeve being adapted to engage the
heddle bar on opposite sides of the flattened
portion of the pin, and means other than the
heddle bar operative to limit the movement of
said sleeve in a direction toward the free end
of said pin for preventing accidental removal
of the sleeve when the heddle bar is removed
from the support. 5
